FILM SHRINKAGE CONTROL

Harry William Menke, Los Angeles, Calif., assignor to Cinemacolor Corporation, Chicago, Ill., a corporation of Delaware

Application May 3, 1930. Serial No. 449,669

7 Claims. (Cl. 91—70)

This invention relates to a method and apparatus for controlling the shrinkage of photographic film generally, and the film used for the production of motion pictures, particularly, and has for its object the control of such shrinkage whereby the film may be uniformly reduced to its maximum density.

With the above and other objects in view, as will be apparent, this invention consists in the steps and method as well as in the construction, combination and arrangement of parts, all as hereinafter more fully described, claimed and illustrated in the accompanying drawing, wherein:

The figure is a substantially vertical section of an apparatus designed to carry out the present invention.

As is well known, all film, particularly motion picture film, after being processed in the laboratory, is what is known as "green" or uncured; that is to say, such film contains a much larger percentage of moisture immediately after being processed in the laboratory than it contains at later periods. Thus, after the film has been processed after being exposed, the older it becomes the greater the shrinkage. This shrinkage, heretofore, has not been uniform because the portions of the film treated are not processed in the laboratory at the same time, so that where a number of film sections go to make up a complete unitary film, the various sections have reached usually different degrees of density and therefore have shrunk varying percentages due to the varying ages of the respective film sections.

This has proven to be objectionable not only in the production of black and white motion pictures, but it has proven particularly objectionable in the production of motion pictures in natural colors. In processes for the production of motion pictures in natural colors employing two or more images which are to be superposed on the film, either by the use of a single standard film or by two separate films, lack of registration of these superposed images is very often caused by uneven shrinkage frequently in the same scene and almost always in scenes produced and developed at different times. This lack of registration due to shrinkage destroys the color values in the projected images and not infrequently results in complete color distortion.

It has been found that there is a certain point where film shrinks to its greatest density and that after that point has been reached there is little or no further shrinkage or change in the film structure either by expansion or by con-

traction. Heretofore in the production of black and white pictures and in the research incident to the production of motion pictures in natural colors, the compensation of or for the shrinkage of the film has to some extent been accomplished by mechanical adjustment in each printing or projecting machine, but this control or compensation is not constant and to a large extent depends upon the accuracy of each individual machine or skill of the operator.

The present invention is designed to provide a method, as well as an apparatus, for controlling this shrinkage of the film, whereby the film may be at any time brought to its maximum density. Thus, by the use of the present method and apparatus, the film may be reduced to its maximum density immediately after it has passed through treatment by the laboratory, or at any time subsequent thereto; so that a plurality of film sections treated by the present method and apparatus will have substantially the same density and shrinkage irrespective of the time at which the treatment takes place. The present invention also contemplates not only the uniform reduction of the film to its maximum density but also the maintenance of the film in a pliable condition free from brittleness which might otherwise take place by the treatment.

The present invention contemplates the placing of a quantity of film in an approximately air-tight compartment and subjecting it to the action of heat which will drive the moisture from the film. At the top of the compartment is provided an exhaust fan which will remove the moisture driven from the film by the action of the heat from the compartment, thereby eliminating any possibility of precipitation. While the film is being so treated for the reduction thereof to its maximum density, it is being constantly sprayed by a solution suitable for maintaining the film in a pliable condition free from brittleness.

It is to be understood that the film may pass through the compartment or cabinet automatically or manually. It has been found that at a temperature of 150 degrees F. the film will reach its maximum density in substantially one hour and that it is possible to pass the film through the cabinet or compartment automatically in such manner that each portion of the film will remain within the cabinet substantially one hour subject to the heat of 150° F. Automatic controls may be provided which will regulate the speed of the passage of the film through

the compartment or cabinet dependent upon the heat maintained in the compartment or cabinet. The automatic features of the method and apparatus form no part of the present invention and therefore will not be here described in detail.

Reference being had more particularly to the drawing 10 designates a substantially air-tight cabinet having a series of rollers 11 at or adjoining its top and a series of similar rollers 12 at or adjoining its bottom. Below the floor of the cabinet or at the bottom thereof is a heating element, 13, here shown as an electrical element but which, of course, may be any other suitable means for supplying the required heat to the interior of the cabinet. Opposed to the heating element 13 is an exhaust opening 14 in which is positioned an exhaust fan 15 operated in any suitable manner. At one side of the cabinet 10 and adjoining the bottom thereof is an inlet opening 16 while directly opposed thereto is an outlet opening 17. Coacting with the inlet opening is a feeding reel 18 while a take-up reel 19 coacts with the outlet opening 17.

It is to be observed that the rollers 11 of one row are staggered with respect to the rollers 12 of the opposite row whereby the film entering the cabinet through the opening 16 from the feeding roll 18 may pass alternately over the several sets of rollers 11 and 12 thereby increasing the quantity of film passing through or in the cabinet and permitting the several laps of the film in the cabinet to rest substantially parallel and in spaced relation. After the film has been passed alternately over the rollers 11-12 it is fed through the outlet opening 17 and connected to the take-up reel 19. The film upon the rollers 11-12 within the cabinet 10 will reach its maximum density within substantially one hour if the heat therein is maintained at substantially 150° F. Of course, if the heat exceeds 150° F. the film must be removed from the cabinet more quickly and if it falls below 150° F. it must be allowed to remain in the cabinet for a greater period of time.

In order to maintain the film pliable during and after its treatment by the present process, a compression tank 20 is placed at the side of the cabinet 10 and is connected by a pipe 21 extending vertically upon the interior of the cabinet, with the horizontal spray pipes 22 located respectively at the top and the bottom of the cabinet. The pipe 21 communicates with an auxiliary container 23 in which is placed the solution used for the treatment of the film. By opening the valve 24 of the air tank, the passage of air through the pipe 21 will remove the solution from the container 23 drawing it into the pipe 21 to force it outwardly through the perforations of the spray pipes 22 which direct the spray so created to and over the body of the film within the cabinet 10.

The solution in the container 23 consists of approximately two parts alcohol, four parts glycerin and one part oil of cedar intimately mixed. This solution when sprayed upon the film as above described prevents the film from becoming brittle or hard but at the same time does not prevent the film from reaching its maximum density. It is of course, to be understood that the proportions of the solution above described may be varied or even the elements changed without departing from the spirit and scope hereof.

In the operation of the apparatus heretofore described, a motor 25 is connected to the take-up

reel 19 and is designed to draw the film, indicated generally as F through the cabinet and wind it upon the take-up reel 19. If the speed of this motor is such that any given point of film would take one hour to pass through the cabinet while the temperature therein is 150° F. the motor may operate continuously at that speed and the film passing through the cabinet will reach its maximum density. If, however, the temperature rises above 150° F. the speed of the motor 25 should be increased, while if the temperature falls below 150° F. the speed of the motor should be reduced. If the temperature, however, is maintained at substantially 150° F. by a suitable thermostatic control the speed of the motor may remain approximately constant whereby each portion of the film F will be substantially an hour in passing through the cabinet.

In order that only film to be treated will be in the cabinet, the film may be attached to a leader or blank film which is threaded through the machine and wound upon the take-up reel until the cabinet is filled with the film to be treated.

From the foregoing it is apparent that a method and apparatus is produced which will bring film to its maximum density without decreasing the pliability or strength of the film.

What is claimed is:

1. The method of controlling the shrinkage of uncured film consisting in enclosing the film, subjecting it to heat for a time duration sufficient to shrink the film to its point of greatest density, while exhausting the air from around the film and treating the film with a solution capable of maintaining the film pliable.

2. The method of controlling the shrinkage of uncured film consisting in enclosing the film, exhausting the air from around the film, subjecting it to approximately 150° F. for substantially one hour whereby the greatest density of the film is secured, and simultaneously treating the film to counteract the tendency to become brittle.

3. The method of controlling the shrinkage of uncured film comprising subjecting the film for substantially one hour to a dry heat of approximately 150° F. whereby the greatest density of the film is attained and simultaneously treating the film to counteract the tendency to become brittle.

4. The method of controlling the shrinkage of film consisting in subjecting the film for substantially one hour to a dry heat of approximately 150° F. and simultaneously treating the film with a solution of alcohol, glycerine and oil of cedar.

5. The method of controlling the shrinkage of film consisting in enclosing the film and arranging it in parallel spaced laps, subjecting it to a heat of 150° F. for one hour, exhausting the air from around the film, and treating the film with a solution of alcohol, glycerine and oil of cedar.

6. The method of controlling the shrinkage of uncured film comprising subjecting the film to the action of heat for a time period sufficient to shrink the film to its point of greatest density, and simultaneously treating the film to counteract the tendency to become brittle.

7. A step in the method of controlling the shrinkage of uncured film which consists in subjecting the film to the action of heat for a time period sufficient to shrink the film approximately to its point of greatest density while simultaneously removing air from around the film.
